UNITED STATES PATENT OFFICE.

WILLIAM C. STUCKEL, OF NEWARK, NEW JERSEY.

PIN-PROTECTOR.

997,474.

Specification of Letters Patent. Patented July 11, 1911.

Application filed July 11, 1910. Serial No. 571,279.

To all whom it may concern:

Be it known that I, WILLIAM C. STUCKEL, a citizen of the United States, residing at Newark, in the county of Essex and State of New Jersey, have invented certain new and useful Improvements in Pin-Protectors; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to an improved protector or fender for the ends of hat pins, and is adapted to be affixed to the point of the pin where the point projects beyond the wearer's hat, and when so affixed, to act as 20 a protection against the accidental injury of any one who might come in contact with the pin point.

The device is a thimble or ferrule which has a closed end and is filled from side to 25 side with material that is somewhat elastic and is adapted to be penetrated by a pin point, and which, when so penetrated, clings to the pin by its natural elasticity so that force must be used to remove the thimble 30 from the pin. The thimble is preferably made smaller at its closed end than it is at its open end, and the grasping material fitting closely in the thimble, the fit of the pin point in the material becomes tighter as it is 35 forced in. The surface of the material that is presented to the pin point extends from side to side of the thimble and the whole surface of the material is presented to the pin point and no time is wasted finding an 40 entrance for the pin point, as it can be forced into the material at any point. This feature also admits of the utilization of all the material, that is apt to be used as much on its edges as at the center. The thimble 45 can be provided with a flaring open end, if desired, so as to facilitate the placing of the thimble on the pin.

The invention is illustrated in the accompanying drawing, in which—

50 Figure 1 is an elevation of a pin with the thimble attached. Fig. 2 is an enlarged section of the thimble. Fig. 3 is an end view of the same, and Fig. 4 is a modified form.

The device is adapted for use with any 55 form of hat pin 10 having a point 11 on one

end and a head 12 on the other end. The thimble 13 is made of any suitable material, preferably metal, and can be ornamented as desired. The thimble has an open end and a closed end and is preferably tapered toward 60 its closed end so that it forms a truncated cone. The thimble has a block of material 14 therein which can be fixed by an adhesive or driven in and held by its own friction on the sides, since an elastic material is used 65 to make up the block. The material best adapted for the purpose is cork, but other materials might be employed. The whole block fills the thimble from side to side and presents its whole imperforate transverse 70 area for penetration by the pin point 11. The narrowing formation of the thimble makes the pin fit tighter as it goes in and causes a tight binding of the thimble on the pin, through the adhesion of the material 14 75 in the block, to the pin, this being evident from Fig. 3. The construction which thus permits the whole surface of the material 14 to be available gives long life to the block of cork or the like, since the whole 80 surface is used up and not any particular channel in it. If desired the open end of the thimble can be made with a flare, as at 15 in Fig. 4, which facilitates the "finding" of the cork by the pin, and thus makes the 85 device more convenient for use.

The tapered construction of the thimble causes the block of elastic material to be compressed on its inner end when it is forced, in the process of manufacture, to its place in 90 the thimble so that the tight compression which increases toward the small end of the tapered thimble, and of the block, causes more resistance to the pin point as the pin point continues to penetrate the elastic block, 95 and under normal conditions with normal pressure on the pin head, the point will not penetrate to the back end of the thimble and become dulled or damaged on the point.

Having thus described my invention, what 100 I claim is—

A protector for hat pins comprising a thimble having an open end and a closed end, the closed end being smaller than the open end whereby the thimble is provided 105 with a taper, and an imperforate block of elastic material forced into the thimble and compressed on the inner end by reason of the taper of the thimble, the block of elastic material having its whole transverse surface 110

presented for the insertion therein of a pin point, the compression of the inner end of the block causing more resistance to the pin point as the pin point penetrates farther into the block whereby the pin point is prevented, under normal pressure, from engaging the back end of the thimble.

In testimony that I claim the foregoing, I have hereunto set my hand this 28th day of June, 1910.

WILLIAM C. STUCKEL.
